APPARATUS FOR BENDING A CURLED METAL EDGE AROUND A REINFORCING WIRE

Everett M. Hunt, Portsmouth, N. H.

Application June 30, 1945, Serial No. 602,637

6 Claims. (Cl. 153—39)

(Granted under the act of March 3, 1883, as amended April 30, 1928; 370 O. G. 757)

1

My invention relates to a forming machine. It has to do, more particularly, with a machine for bending the edge of a relatively thin section of metal around a reinforcing wire or rod of metal.

In producing metal articles from relatively thin sections of metal, it is desirable to incorporate in the edge of the metal section, a reinforcing wire or rod of metal. To do this, it is necessary to bend the edge of the metal section around the reinforcing wire associated therewith so that the wire will be retained firmly in position.

The object of my invention is to provide a simple machine which is very effective to form the edge of a relatively thin metal section around a reinforcing metal wire which is associated therewith.

The embodiment of my invention disclosed in this application comprises a machine which is adapted to bend the edge of the flange or sidewall of a metal pan around a reinforcing wire or rod of metal. However, it is to be understood that my invention is not limited to the manufacture of pans.

In producing metal pans, such as large rectangular baking pans, the flange or sidewall is formed with a curled edge so that an open wire-receiving channel of hook-shape cross-section is provided which receives the wire and which must be bent around the wire to completely enclose it. My machine receives the partly formed pan with the wire in position in the channel and by means of relatively movable cooperating metal shaping dies, the walls of the channel are bent around the wire in firm embracing relationship therewith.

The preferred embodiment of my invention is illustrated in the accompanying drawings wherein similar characters of reference designate corresponding parts and wherein:

Fig. 1 is a side elevational view of a machine constructed according to my invention.

Fig. 2 is a front elevational view of the upper portion of the machine shown in Fig. 1.

Fig. 3 is a top plan view, partly broken away, of the machine shown in Figs. 1 and 2.

Fig. 4 is a vertical sectional view taken substantially along line 4—4 of Fig. 3.

Fig. 5 is a partial end view of my machine.

Fig. 6 is a vertical sectional view taken substantially along line 6—6 of Fig. 3 but showing the forming dies in their initial inoperative positions rather than as in Fig. 3.

Fig. 7 is a view similar to Fig. 6 showing the forming dies in their final operative positions as shown in Fig. 3.

Fig. 8 is an enlarged detail in vertical section

2

showing the forming dies in their initial inoperative positions.

Fig. 9 is a view similar to Fig. 8 showing the forming dies in their final operative positions.

With reference to the drawings, I have illustrated a machine which is designed to receive a metal pan 1 of square or rectangular form which may be a metal baking pan. The pan is shown in inverted position in Figs. 6 to 9 and includes a flange or sidewall 2. The flange 2 has a turned edge 3 (Fig. 8) of hook-shape cross-section so as to form a channel 4 for receiving a reinforcing wire or rod 5 of metal. My machine is adapted to bend the hook-shape edge 3 around the wire 5 into tightly embracing relationship (Fig. 9) to the wire so as to retain it in position on the flange.

My machine, as shown best in Figs. 1 to 3, comprises a table 6 or other suitable support. This table includes the top plate 7 which carries most of the mechanism of my machine. It also includes a supporting beam 8 which is suitably connected to the legs of the table adjacent their lower ends. The supporting beam 8 supports an upstanding cylinder and piston unit 9, at the center of the table, which is secured thereto by means of bolts 10. The fluid-actuated cylinder and piston unit 9 is controlled by a suitable valve unit 11 which is disposed in front of the table 6 and is actuated by a foot pedal 12. The valve 11 is connected to unit 9 by the lines 13 and 14. A source of fluid pressure is connected to valve 11 by a line 15.

The piston rod 16 of unit 9 extends upwardly therefrom and has pivoted to its upper end, as at 17, the lower end of a link 18. The opposite end of link 18 is pivoted within the yoke 19 (Fig. 3) formed on one end of a lever 20. The opposite or rear end of lever 20 is pivoted, as at 21, to an upstanding support 22 which is a part of and at the rear end of a U-shape support 23 secured to the upper surface of the plate 7. Within the U-shape support 23 is a large aperture 24 formed in plate 7 to permit the proper movement of link 18 and lever 20. When piston rod 16 is in its uppermost position, the link 18 will be vertically disposed in substantial alignment with rod 16 and the lever 20 will be in slightly rearwardly inclined position, as indicated by the full lines in Fig. 1. When the piston rod 16 is in its lowermost position it will be withdrawn practically completely within the unit 9 and the link 18 and lever 20 will be sharply inclined downwardly and forwardly as indicated by the dotted lines in Fig. 1.

The yoke 19 (Fig. 3) on the end of lever 20 is also pivoted to a yoke 25 disposed therewithin and which is formed on the end of a link 26. The opposite end of link 26 is provided with a sleeve 27 which surrounds and freely rotates on a shaft 28. The shaft 28 extends transversely of the table and each of its ends is keyed within a collar 29 formed on the end of a rocking arm 30 disposed at each side of the table. The other end of each arm 30 is keyed on a second transverse shaft 31 which is parallel to the shaft 28 but at a lower level. Each end of the shaft 31 is rotatably mounted in an upstanding bearing plate 32 (Figs. 3 and 4) which is a part of the plate 7. It will be apparent that movement of piston rod 16, link 18 and lever 20 between the full-line and dotted-line positions indicated in Fig. 1 will exert a push and pull on the link 26 which will exert a corresponding force on shaft 28 and will, thereby, swing the arms 30 about the axis of shaft 31 between their rearwardmost positions, indicated by the dotted lines in Fig. 1, and their forwardmost positions, indicated by the full lines in such figure.

Between the bearing plates 32 and the arms 30 the shaft 31 carries the eccentrics 33 (Fig. 3) which are keyed thereon. Each of the eccentrics 33 (Fig. 5) fits into a cooperating opening formed in the rear end of a link 34. The forward end of each link 34 is pivoted to a small yoke 35 for movement of said link in a vertical plane. The yoke 35 is threaded on the rear end of a bolt 36 which is slidably carried by a laterally projecting lug 37 which extends from a vertical flange 38. The forward end of the bolt 36 carries a small block 39 which has a guide formed on its inner edge so that it will be supported on and slide along the flange 38. Disposed between the relatively movable lug 37 and block 39 are compression springs 40 which have their ends engaging such members and fitting over small locating pins carried thereby.

The flanges 38 are formed on the ends of a transversely extending movable die-carrying plate 41 (Figs. 2, 3, 4, 6, and 7) which extends the full width of the table and is disposed at the forward edge thereof. On the inner surfaces of the flanges 38, guideways 42 (Fig. 2) are provided which fit around the edges of a stationary plate 43. The plate 43 is supported slightly above the plate 7 by three laterally spaced blocks 44 which are suitably secured to both plates. Thus the plate 41 may slide forwardly and rearwardly on the plate 43. When the shaft 31 and the eccentrics 33 are rocked by the rocking of the arms 30, the links 34 will be moved back and forth. A pan edge supporting shelf is provided in the form of an angle member disposed along the rear edge of the plate 43. The shelf 45 (Figs. 6 and 7) is bolted to the blocks 44 by bolts 46 in such a manner that its upper surface is flush with the upper surface of plate 41.

The upper surface of the plate 41 supports an inner supporting die 47 which is bolted thereto by means of bolts 48. This die has a rear inclined edge 49 which will be of the same inclination as the flange 2 of the pan which will be disposed in inverted position over the die. The die is made from a series of sections (Fig. 2) so that its length may be changed, by removing or adding sections, to correspond to that of pan 1. The die is so mounted that it extends rearwardly beyond the plate 41 and into overlapping relationship with the shelf 45. When die 47 is moved rearwardly, its rear edge will reach the rear edge of shelf

45 before the rear edge of plate 41 contacts with the forward edge of shelf 45, as indicated in Figs. 4 and 7.

The shaft 28, which is carried by the rocker arms 30, also has associated therewith a pair of die-actuating links 50, as shown in Figs. 1, 2, 3, 6 and 7. These links are located on the shaft 28 adjacent its outer ends near the arms 30. The shaft 28 extends through a slot 51 formed in each 10 of the links 50. The rear end of each slot has an adjustable stop 52 slidably mounted therein which is adjustable by means of a bolt 53 threaded through the rear end of the link and connected to the stop. The forward end of each of the links 15 50 is keyed on the end of a transverse shaft 54. Inside of each of the links 50, the shaft 54 carries a die-actuating arm 55 which has its upper end rotatably mounted on the shaft. Stop collars 56 (Figs. 2 and 3) keyed to shaft 54 prevent longitudinal movement of such shaft.

The lower end of each arm 55 is cut out to embrace the angular cross-section portion of a die-carrying member 57. The arm may be welded or otherwise secured to the member 57. The member 57 extends transversely of the table and is rotatably mounted by means of cylindrical bearing sections 58 (Figs. 3, 4, and 6) on its ends which are rotatably disposed in bearings formed in the vertical plates 32 and by semi-cylindrical bearing sections 59 (Fig. 4) which cooperate with semi-cylindrical bearings 60 formed in an upstanding portion 61 at the rear end of each of the blocks 44. These cooperating bearings 59 and 60 will take the rearward thrust developed on member 57 during the forming operation.

It will be apparent that when the shaft 28 is swung forwardly by link 26, it will move forward in slots 51 in links 50 without moving the links. The shaft will eventually contact the forward 40 ends of slots 51 and will push the links 50 forwardly. This swings the arms 55 forwardly and rotates the die-carrying member 57 counterclockwise. When the shaft 28 is moved rearwardly, the shaft will move in the slots 51, without moving links 50, until the shaft contacts the stops 52 at which time the links 50 will be pulled rearwardly, thereby rotating the die-carrying member 57 clockwise. When the shaft 28 moves rearwardly it will contact with rubber stops 23a (Fig. 51) which are carried on the forward and upper corners of the U-shape support 23 and thereby the extent of rearward movement of the shaft and associated parts will be limited. This will prevent movement of pivot point 17, between link 18 and lever 20, past dead center and thereby interfering with subsequent operation of this linkage by unit 9.

The member 57 is provided with a die-receiving socket 62 extending substantially the full length thereof. This socket will receive the forming die 63 which is preferably made of a plurality of sections so that it can be readily changed in length to correspond to that of various pans upon which the machine will operate. The die 63 is held in the socket 62 by means of a plurality of retainer strips 64 which are bolted to member 57 by bolts 65 (Fig. 7). These strips have outer bevelled edges 66 that contact an inclined shoulder on the inner edge of the die and wedge it in the socket 62 firmly against the outer edge thereof.

The die 63 is provided with a forming channel 67 (Figs. 8 and 9) extending the full length thereof and being of proper size and cross-sectional 75 shape to form the reinforcing wire containing

bead on the pan. The cross-section of this channel is slightly greater than a semi-circle and its center is at the axis of rotation of the member 57. The die 63 may be removed and replaced quickly with a die having a different size channel if reinforcing wire of a different size is to be used. The radius of the channel will be that of the reinforcing wire plus the thickness of the metal of the flange of the pan.

In using my machine, the pan is inverted and placed over the inner die 47 in the manner indicated in Figs. 6 and 8. The die 47 will be in its forwardmost position at this time so that the flange of the pan to be bent will have its hooked edge 3 resting on the shelf 45. At this time, the arms 55 will be in their rearwardmost position and the member 57 will have been rotated clockwise to the extent of its movement. The wire 5 will be in position in the channel 4 on the flange 2 of the pan 1.

The pedal 12 is now actuated to cause the unit 9 to actuate the mechanism of my machine. This will swing the shaft 28 and arms 30 forwardly in the manner previously indicated. The shaft 31 will be rotated and, consequently, the eccentrics 33 will be rotated and they are so disposed on the shaft that a rear pull will be exerted on the links 34, causing the die 47 to move rearwardly towards the die 63. An instant after the die 47 is moved towards the die 63, the die 63 is rotated towards the die 47. This is accomplished by the shaft 28 which, when it is moved forwardly, engages the forward ends of slots 51 in arms 50 and thereby swings arms 55 forwardly. However, this movement is delayed until the movement of die 47 has started so that the rear edge of die 47 will reach the rear edge of shelf 45 before the die 63 acts on the edge 3 of the flange 2. This time interval may be adjusted by adjusting the bolts 53 on arms 50 and thereby, adjusting the effective lengths of the slots 51.

As the die 47 moves rearwardly, the edge 3 of the flange of the pan will be slid rearwardly on the shelf 45 until it is completely off the shelf. However, shortly before this happens the edge 3 of the flange is engaged by the hook-shape forming edge 68 of the die 63 and is bent forwardly around the wire 5. When the edge 3 is bent forwardly beyond the center of the wire 5, the hook-shape forming edge 68 serves to draw the edge 3 into the channel 67 of the die 63. The die 47 continues to move the flange 2 towards the die 63 which continues to rotate towards the flange and by the time the edge 3 slides off the shelf 45, the turned edge 3 is completely supported within the channel 67. The die 63 will continue to rotate until the edge 68 contacts the outer surface of the flange 2 as shown in Fig. 9, at which time the wire 5 will be firmly embraced by the turned edge 3. The die 47 reaches the extent of its rearward movement before rearward movement of links 34 is completed. As the links 34 continue to move rearwardly a pull will be exerted on the bolts 36, thereby causing the springs 40 to be compressed. This will ensure that the dies 47 and 63 will be firmly but yieldingly pressed towards each other during the formation of the flange of the pan disposed therebetween. Consequently, as the rotation of die 63 nears its final phase, it may move the die 47 forwardly slightly due to the yielding or resilient connection of plate 41 to links 34. The rear edge of plate 41 will not contact with the shelf 45 and thereby interfere with the yielding or resilient association of the dies 47 and 63 during the forming operation.

When the unit 9 is actuated again to return the shaft 28 and arms 30 to their rearwardmost positions, the member 57 will be rotated clockwise to its original position and the die 47 will be moved forwardly to its original position. Due to the provision of slots 51 in arms 50, rotation of member 57 will be delayed for an instant until the die 47 starts to move forwardly and exposes the shelf 45 for supporting the flange 2 of the pan. The die carrying member 57 is provided with a cutaway lower edge 69 (Fig. 6) extending the full length thereof, to prevent interference with the lower corner of the rear edge of shelf 45 as the member 57 is rotated to its original position.

It will be apparent from the above description that I have provided a simple machine which is very effective to form the edge of a relatively thin section of metal around a reinforcing metal wire or rod. As previously indicated, this invention is not limited to the manufacture of pans but a pan has been used merely as one example of work upon which this machine can be used.

The invention described herein may be manufactured and used by or for the Government of the United States of America for governmental purposes without the payment of any royalty thereon or therefor.

What I claim is:

1. A metal forming machine for use on a metal section having a curled edge with a reinforcing wire disposed therein, comprising a structural framework including a shelf for supporting said curled edge, a supporting die for engaging the surface of the metal section opposite the curled edge, said die being movable relative to the edge of said shelf, a forming die disposed along the edge of said shelf, said supporting and forming dies being supported upon said structural framework, said forming die having a hook-shape forming edge along the side of an edge-receiving and forming channel which is formed therein, means for moving said supporting die towards the edge of said shelf, said moving being operative to bring the curled edge into association with said forming die, means for rotating said forming die towards said supporting die, and means operative during the rotation of said forming die to cause the hook-shape forming edge thereof to swing towards and engage said curled edge and to draw it into said channel as it bends it around the wire, means including the movement of said supporting die for pushing said curled edge off said shelf, said curled edge being drawn into said channel before said curled edge is pushed off said shelf.
2. A structure according to claim 1 wherein said moving means for the dies includes a yielding connection so that the dies will yieldingly cooperate with each other.
3. A structure according to claim 1 wherein means is provided for causing the means for moving the supporting die towards the edge of said shelf to function shortly before the means for rotating the forming die.
4. A metal forming machine for use on a metal section having a curled edge with a reinforcing wire disposed therein comprising a structural framework including a shelf for supporting said curled edge, a supporting die for engaging the surface of the metal section opposite the curled edge, said die being movable relative to the edge of said shelf, a forming die disposed along the edge of said shelf, said supporting and forming dies being supported upon said structural framework, said forming die having a hook-shape forming edge along the side of an edge-receiving and

forming channel which is formed therein, a rockable shaft attached to said structural frame, eccentrics associated with said rockable shaft, means for moving said supporting die relative to the edge of said shelf, said means including links connected to said rockable shaft by means of said eccentrics, means for rotating said forming die relative to said supporting die, said means including rocking arms connected to said forming die, rocking arms for said shaft, and means for rocking said die-actuating arms and said shaft actuating arms, said last mentioned means including lost-motion linkage for delaying actuation of said die-rocking arms relative to actuation of said shaft-rocking arms.

5. A structure according to claim 4 wherein said lost-motion linkage is adjustable to vary the time interval between actuation of the die-rocking arms and the shaft-rocking arms.

6. A structure according to claim 4 wherein 10 said links for moving said supporting die include yielding connections.
